UNITED STATES PATENT OFFICE.

MINOR F. H. GOVERNEUR, OF ROCHESTER, NEW YORK, ASSIGNOR, BY MESNE ASSIGNMENTS, TO LOCKE INSULATOR CORPORATION, OF BALTIMORE, MARYLAND, A CORPORATION OF MARYLAND.

INSULATOR.

Application filed July 29, 1919. Serial No. 313,976.

To all whom it may concern:

Be it known that I, MINOR F. H. GOVERNEUR, a citizen of the United States, residing at Rochester, in the county of Monroe and State of New York, have invented certain new and useful Improvements in Insulators; and I do hereby declare the following to be a full, clear, and exact description of the invention, such as will enable others skilled in the art to which it appertains to make and use the same.

The invention relates to insulators for use in connection with transmission lines for high voltage currents, and more particularly to new and improved means for effectively connecting the eye-bolts or equivalent fastening means to suspension insulator units.

To this end the principal object of my invention, broadly stated, is to provide a strong and reliable means for connecting eye-bolts to the porcelain of insulators, said means comprising a metallic member connected to said eye-bolt and adapted to be entered within the bolt receiving socket of an insulator and then enlarged so as to prevent the withdrawal of the said bolt.

Another object of the invention, is to provide an eye-bolt with a hollow cap or thimble of relatively soft metal, said cap or thimble being connected to the eye-bolt so as to extend beyond the end of the same whereby the said cap may be entered within the bore of an insulator adjacent the enlargement therein and means for expanding the said cap or thimble so as to substantially fill the enlarged portion of the said bore, whereby the eye-bolt is interlocked with the insulator.

There are other objects of the invention as will hereinafter appear from the description of the single embodiment of the invention which has been illustrated on the accompanying drawings, in which,—

Figure 1 is a transverse vertical section through the porcelain and eye-bolt of a suspension insulator unit, showing the invention.

Figure 2 is a fragmentary view showing the position of the eye-bolt, and associated cap or thimble with reference to the insulator body before the cap is expanded;

Figure 3 is a view similar to Figure 2, showing the cap in expanded position; and

Figure 4 is a view, in side elevation, of the eye-bolt and associated cap or thimble.

Throughout the specification and drawing like parts are designated by like reference characters.

Before describing the single embodiment of the invention, it is here pointed out that by the term "eye-bolt" I do not intend to limit my invention, since the term is employed in its descriptive and not in the limiting sense.

The numeral 1 designates the porcelain or body portion of a suspension insulator unit, the said porcelain is preferably provided with a neck or stem 2 having a groove 3, at the juncture of said stem and the skirt portion 4 of the insulator, said groove being adapted to receive the means by which the bell shaped cap (not here shown) is connected to the porcelain body of the insulator. Entering from the underside of the skirt portion 4 there is provided a cylindrical bolt receiving socket or bore 5, which is preferably provided adjacent the upper end with an enlargement 6.

The eye-bolt 7 is provided at one end of stem 9 with a hoop or eye 8 and at the other end of the stem there is provided a hollow cap or thimble 10. The said cap may for convenience be formed by brazing or welding a soft metallic bulb to the end of the eye-bolt. An opening 11 in the stem 9 of the said bolt leads to the interior of the cap 10. The side walls of the said cap are formed of relatively thin metal, so that they will deform under excessive pressure.

The thimble 10, which is provided with relatively thin side walls, is welded or brazed to the end of the stem 9 of the eye-bolt 7, the latter having been previously provided, with an opening leading to the end of the eye-bolt which is surrounded by the thimble. The bolt and associated thimble are entered within the opening 5 of the porcelain until the cap 10 occupies a position within the enlargement 6 of the said recess 5. When in this position pressure is applied to the interior of the thimble or cap 10 through the hole 11 in the eye-bolt, and the thimble or cap is expanded until it substantially fills the enlargement 6 of the bore or recess 5, care being taken to provide sufficient room between the enlarged cap and the walls of the recess to permit of ex-

pansion and contraction of the members without bringing pressure to bear on the porcelain. A convenient way to expand the thimble is to apply hydraulic pressure there-
to, the opening 11 serving as means to admit the application of pressure to the interior of the thimble.

By the form of connection hereinbefore described, there is provided a permanent connection between the eye-bolt and the porcelain. The connection while permanent is, nevertheless, flexible to a high degree and this flexibility is not obtained either at a sacrifice of strength of porcelain or bolt. By having a space between cap and porcelain I am enabled to obtain the flexible connection referred to above and at the same time I relieve the porcelain of expansion strains from the eye-bolt.

To reinforce the thimble or cap after the same has been expanded I may fill the cavity within the cap with type metal or other

like metal having a comparatively low melting point. This character of filling has been diagrammatically illustrated as at 12.

Having now described my invention what I claim and desire to secure by Letters Patent is:—

An eye bolt for insulators comprising a shank portion having a tubulature there-
through, one end of which shank is pro-
vided with means for engaging a co-acting member, the opposite end of said shank hav-
ing connected thereto, in fluid-tight relation,
an imperforate, hollow, thin-walled, soft-
metal thimble communicating with said
tubulature, whereby said bolt is adapted
for connection with an associated portion
by inserting said thimble in a correspond-
ing aperture in said portion and expanding
the same in place.

In testimony whereof I affix my signature.

MINOR F. H. GOUVERNEUR.
